UNITED STATES PATENT OFFICE.

FRED R. KUNKEL, OF WILKINSBURG, PENNSYLVANIA, ASSIGNOR TO
WESTINGHOUSE ELECTRIC & MANUFACTURING COMPANY, A COR-
PORATION OF PENNSYLVANIA.

RHEOSTAT.

No. 832,912.

Specification of Letters Patent.

Patented Oct. 9, 1906.

Application filed June 12, 1905. Serial No. 264,870.

To all whom it may concern:

Be it known that I, FRED R. KUNKEL, a citizen of the United States, and a resident of Wilkinsburg, in the county of Allegheny and State of Pennsylvania, have invented a new and useful Improvement in Rheostats, of which the following is a specification.

My invention relates to rheostats; and it has for its object to provide a simple and improved form of rheostat for special use in connection with small dynamo-electric machines and for similar purposes.

In the construction of fan-motors and other small dynamo-electric machines it is often desirable that the starting and speed-regulating devices be located within the base of the machine, and it is the purpose of my invention to provide a rheostat that may be conveniently employed in such locations.

My invention is illustrated in the accompanying drawings, Figure 1 of which is a view in bottom plan of a motor provided with a rheostat constructed in accordance therewith. Fig. 2 is a view in vertical section through the base of the motor and in side elevation of the rheostat shown in Fig. 1. Fig. 3 is a view in vertical section through the rheostat and a portion of the base of the motor. Fig. 4 is a view in side elevation of a portion of the rheostat, and Fig. 5 is a diagrammatic view of the circuit connections of the motors.

Secured to the under side of the base 1 of a motor 2 by means of screws 3 and 4 is a circular block 5, of porcelain or other suitable insulating material, to which a conducting switch-arm 6 is pivotally secured by means of a bolt 7. The switch-arm 6 is adapted to engage near its middle a conducting-strip 8, that is secured to the insulating-block by means of screws 9 and 10 and at its outer end contact-terminals 11, 12, 13, and 14, a clip 15 being connected to the terminal 14 and forming one terminal of the rheostat.

The periphery of the block 5 is provided with flanges 16, 17, 18, 19, &c., alternate ones of which occur on opposite edges, the flanges being arranged in this manner for the purpose of facilitating molding of the porcelain. On the cylindrical surface of the block between the flanges a resistance-conductor 20 is wound the terminals of which are connected with contact-terminals 12 and 14,

respectively, and a point intermediate the terminals with contact-terminal 13, the leads being located in notches 21, 22, and 23 in flanges at the periphery of the block.

An insulating-bushing 24 is screwed in the base 1 of the motor for the purpose of protecting the conductors 25 and 26, which connect terminal-clips 15 and 27, respectively, with the supply-circuit, a corresponding aperture 28 being provided in the porcelain block, through which the conductors pass. The terminals of the motor 2 are connected, respectively, with conducting-strip 8 and terminal-clip 27, as shown in Fig. 5, and the amount of resistance in the circuit of the motor is regulated by varying the position of the switch-arm 6. The block 5 is provided with spaced apertures 29, in which screws 30 may be located when it is desired to secure the base of the motor to a vertical wall or in any other suitable position.

I claim as my invention—

1. The combination with a motor having a hollow base, of a rheostat located in said base and comprising an insulating-block having peripheral edge flanges, a resistance-conductor located on the periphery of the block between the flanges, and a switch mechanism connected with the resistance-conductor and located on the surface of the block.

2. The combination with a motor having a hollow base, of a rheostat located in said base and comprising an insulating-block having integral flanges projecting from its peripheral edges, a resistance-conductor located on the periphery of the block between the flanges, switch mechanism located on the surface of the block and connected with the resistance-conductor, and means for fastening said block to a supporting-base.

3. A rheostat comprising an insulating-block having flanges projecting from its periphery, the flanges on opposite edges being staggered, a resistance-conductor located in the edge of the block, and switch mechanism connected with the resistance-conductor and located on the surface of the block.

4. The combination with a motor having a hollow base, of a rheostat comprising an insulating-block, a resistance-conductor located on the periphery of the block, contact-terminals connected to the resistance-conductor and secured to the face of the block,

a movable switch member pivotally secured to the block for engaging said terminals, and means for fastening said block within the motor-base.

5. The combination of a motor having a hollow base and a regulating-rheostat therefor that is located within the hollow base, comprising an insulating-block, a resistance-conductor located in the periphery of the

block, and switch mechanism located on the surface of the block.

In testimony whereof I have hereunto subscribed my name this 6th day of June, 1905.

FRED R. KUNKEL.
